UNITED STATES PATENT OFFICE

153,963

DESIGN FOR A DOLL OR SIMILAR ARTICLE

Maurice Marossi and Gertrude Cornell,
New York, N. Y.

Application April 21, 1948, Serial No. 145,876

Term of patent 3½ years
(Cl. D34—4)To all whom it may concern:

Be it known that we, Maurice Marossi and Gertrude Cornell, citizens of the United States, residing at New York city, in the county of New York and State of New York, have invented a new, original, and ornamental Design for a Doll or Similar Article, of which the following is a specification, reference being had to the accompanying drawing, forming part thereof.

In the drawing:

Fig. 1 is a front view of a doll, showing our new design;

Fig. 2 is a side view; and

Fig. 3 is a rear view.

We claim:

The ornamental design for a doll or similar article, as shown.

MAURICE MAROSSI.
GERTRUDE CORNELL.
